UNITED STATES PATENT OFFICE.

LEO W. MANION, OF CANTON, OHIO.

MUFFLE FURNACE.

Application filed December 14, 1921, Serial No. 522,251. Renewed June 4, 1928.

- This invention relates to improvements in muffle construction for furnaces such as are used for burning or fusing enamels on steel or cast iron ware, or for annealing, heat 5 treating or tempering or other purposes where it may be desirable or necessary to prevent the gases of combustion from coming into contact with the articles within the burning or working chamber.
- 10 The enamels must be burnt or fused in a chamber free from smoke and gases of combustion which would dull the gloss upon the enamel. It is usual to provide a muffle or inner lining in the furnace, the ware being placed within the chamber surrounded by the muffle, while the heated gases completely surround the muffle, but are prevented from passing into the burning chamber and into contact with the ware.
- 15 In order to obtain the proper working temperature within the burning chamber, it is necessary to produce a considerably higher temperature outside of and around the muffle, a considerable loss taking place in 20 conducting heat through the muffle. The muffle tile must necessarily be thin to allow for proper radiation and the exceedingly high temperatures quickly burns out these tile by developing cracks which allow gases 25 and smoke to enter the burning chamber ruining the ware.

The objects of the present invention are to provide a muffle type furnace in which the muffle is so constructed to produce a considerably larger radiating area than is possible with the usual form of muffle furnace, and to provide an improved construction of tile in the muffle which increases the radiation of the muffle, and decreases the possibility of cracking or breaking of the muffle 35 from expansion and contraction due to changes in temperature and also which considerably lessens the cost of installing or repairing the muffle.

40 The invention thus set forth in general terms is illustrated in the accompanying drawings in which—

Figure 1 is a longitudinal sectional view through a furnace embodying the invention; 45 Fig. 2, a section on the line 2—2, Fig. 1; Fig. 3, a section on the line 3—3, Fig. 2; Fig. 4, a perspective view of one of the tile used in the bottom wall of the muffle; 50 Fig. 5, a perspective view of one of the tile used in the supporting arches of the muffle;

Fig. 6, one of the tile carried by the supporting arches; and

Fig. 7, one of the lower row of side wall tiles. 60

Similar numerals refer to similar parts throughout the drawings.

The combustion chamber 1 may be of usual construction, being provided with the bottom wall 2, side and end walls 3 and 4 respectively, and the spaced piles or piers located in parallel rows through the combustion chamber allowing the gases of combustion which enter at the inlets 6 to pass entirely through the combustion chamber 70 and between the piles.

In the usual form of muffle type furnace now in general use, it is common to provide a row of spaced piles or piers only along each side of the combustion chamber, an 75 arch, which forms the bottom part of the burning or working chamber being spanned across said rows of piles. Spaced walls of fire brick are then built upon the arch to receive the burning racks upon which the 80 ware is placed.

It will be seen that this arch, in order to support the weight placed thereon, must necessarily be of considerable thickness, the radiation therefrom being considerably reduced as the heat from the combustion chamber must pass through the thickness of the arch into the working chamber. The walls upon the arch, which support the burning racks, also retard radiation and 90 absorb heat which is radiated into the burning chamber. 85

With the present improved type of muffle, the bottom wall of the muffle is so constructed that the walls for carrying the 95 burning racks are eliminated, the bottom wall of the muffle being shaped to support these burning racks.

A considerably larger radiating area is also provided with this form of muffle and as 100 the weight of the walls above mentioned is eliminated, the bottom wall of the muffle may be constructed of considerably lighter tile, thus providing several times the radiation which is possible with the old form 105 of furnace.

The bottom wall of the muffle is constructed of tiles 7, each of which is provided with the thin panel 8. These tiles may have tongues and grooves 9 and 10 respectively at opposite ends, and 11 and 12 110 respectively at opposite sides, by means of

which adjacent tiles are interlocked, or plain or lapped joints may be provided.

As best shown in Fig. 2, these tiles are supported upon their lower side edges on the piles 5, the upper side edges engaging the next adjacent tiles, thus forming a saw tooth bottom wall in the burning chamber. The peaks thus formed at 13 provide means for supporting the burning racks upon which the ware is placed in the burning chamber.

In the common type of furnace above referred to in which the arch bottom wall is used, it is necessary to provide extremely large piers or piles within the combustion chamber to support the opposite sides of the arch, a very small space being left between the arches for the passage of the gases of combustion. These piers absorb a great amount of heat from the gases of combustion and together with the walls upon the top of the arch which support the burning racks, allow for very little radiation upon the under side of the ware. Especially in the treatment of enamel ware, it has been found essential to heat the under side of the ware to a very high temperature, in order to cause the enamel to fuse with the metal.

With the present construction, the tiles forming the bottom wall of the heating chamber or muffle require very small piers to support the same, it being only necessary to provide piers of sufficient size to support the edges of the tiles. As the tiles forming the bottom wall are supported at their lower edges upon the piers and at their upper edges upon the next adjacent tiles, the structure produced is of great strength, while the radiating surface beneath the working chamber is also considerably increased, the heat radiating from every portion of these bottom tiles.

The side and upper walls of the muffle comprise the spaced columns and arches 14 between which the thin walls 15 are carried. These arches are formed of heavy tiles such as shown at 16 in Fig. 5 and may be composed of cheaper material such as fire clay, while the thin walls 15 are composed of the tiles 17 which may be formed of silicon-carbide or suitable heat resisting alloy metals, which have many times the thermal conductively as well as mechanical strength of the ordinary refractories.

Each of the arch tiles 16 is provided in its upper and lower edges with the respective tongues and grooves 18 and 19 by means of which these tiles are connected and each of these tiles is provided in its side edges with the grooves 20 which receive the side edges of the thin tiles 17. The tiles 17 are also provided in their upper and lower edges with the respective tongues and grooves 21 and 22 for binding the same together.

65 The bottom row of tiles 16* in each side

wall are all made as thick as the tiles 16 and as long as the bottom wall tile 7 so as to span from the middle of one pile 5 to another; and the tiles 16* are provided with the proper tongues and grooves to form joints 70 with each other, and with the adjoining tiles, as shown in Fig. 7.

The usual construction of side and top walls of the muffle comprise a plurality of similar tiles, each of which is formed of an expensive material such as silicon-carbide or the like and each of which has a heavy frame portion around its edges and a thinner, central panel for increasing the radiation. With such a construction, the initial cost of installing the muffle in the furnace, as well as the cost of upkeep is very considerable, while with the present construction, the thin tiles 17 may be formed of considerably less material, thus reducing the cost 80 of the same, while the arch tiles 16 are formed of a cheaper material, thus reducing the initial cost of the muffle as well as the upkeep of the same.

It will also be seen that the thin tiles 17. 90 may be permitted to move within the groove 20 of the arch tiles, due to expansion and contraction, owing to changes in temperature, thus considerably reducing the possibility of breaking or cracking of these tiles 95 from the excessive temperatures to which they must necessarily be subjected.

By referring to Fig. 3 of the drawings, it will be seen that the upper portion of the muffle is supported from the outer wall 3 100 of the furnace by the horizontal wall 24 which extends from the rear end of the furnace to a point intermediate the ends thereof, openings 25 being provided in said wall near the front end of the furnace.

The stack 26 is connected with the rear end of the furnace above the muffle, thus causing the gases of combustion to be drawn upwardly from the combustion chamber through the piles 5 and between the muffle 110 and the outer wall of the furnace and then forwardly to the openings 25, the gases then being drawn rearwardly over the entire top wall of the muffle to the stack.

The gases will thus entirely surround the 115 muffle, heating the same to a high temperature, the heat being radiated through the thin walls of the muffle to the burning chamber. The usual door opening 27 is provided in the forward end of the burning chamber 120 to permit the ware to be placed therein or removed therefrom and is normally closed by a suitable door 28.

It will be evident from the above that a muffle furnace is thus provided which may 125 be installed at considerably less cost than the common form of muffle furnace in which refractories of the same quality are used and which will be capable of producing considerably greater radiation than is possible 130

with the form of muffle furnace now in use. It will also be seen that the supporting walls for the burning racks are eliminated and the possibility of the muffle breaking or cracking is reduced to a minimum, while at the same time the cost of upkeep of the furnace is considerably decreased and repairs may be made to the muffle for a much less cost than is possible at present.

With this construction of muffle the difference in temperature between the burning chamber and the combustion chamber is considerably reduced. In the usual form of muffle furnace it is necessary to raise the temperature of the combustion chamber to 2600° to 3000° F. in order to produce a temperature of 1800° F. within the burning chamber while with the present construction a temperature of 1800° F. may be produced within the burning chamber by raising the temperature of the combustion chamber to only 2000° to 2200° F. This is a great advantage in the operation of the furnace as the excessive heat which it is necessary to maintain in the combustion chamber of the ordinary form of furnace will quickly burn out the refractories comprising the muffle.

For these reasons the improved furnace can be operated with less fuel, than has heretofore been required; and the intervals between the V-shaped ridges in the bottom wall, permit the entrance of the fork usually employed for charging and withdrawing ware from the furnace.

I claim:—

1. In a furnace of the character described, a muffle provided with a bottom wall of substantially uniform thickness throughout its area having alternate similar ridges and depressions, the ridges being arranged to support burning racks and the depressions being arranged to receive charging forks.

2. In a furnace of the character described, a muffle having a bottom wall of substan-

tially uniform thickness throughout its area formed of a plurality of parallel, V-shaped ridges.

3. In a furnace of the character described, a muffle having a bottom wall formed of a plurality of parallel rows of oppositely inclined tiles, means for supporting the lower edges of said tiles, the upper edges of adjacent rows of tiles being joined together to close the wall and support burning racks. 55

4. In a furnace of the character described, a muffle having a bottom wall of substantially uniform thickness throughout its area comprising a plurality of parallel, V-shaped sections, and means below said muffle for supporting the lower edges of said sections. 60

5. In a furnace of the character described, a muffle having side and top walls composed of spaced columns and arches of refractory material and relatively thin walls of refractory material carried by said columns and arches. 65

6. In a furnace of the character described, a muffle having side and top walls formed of spaced columns and arches of relatively 70 heavy refractory material, said columns and arches having grooves in opposite sides and tiles of relatively thin refractory material located in said grooves.

7. In a furnace of the character described, a muffle having side and top walls comprising spaced arches of relatively heavy slightly 75 refractory material and relatively light tiles of highly refractory material supported by said arches. 80

8. In a furnace of the character described, a muffle, a combustion chamber below the muffle, and a corrugated floor wall for the muffle forming the roof of the combustion chamber and comprising similar ridges and depressions arranged to support burning racks and to receive charging forks respectively. 85
